CATALYTIC CONVERSION OF MIXTURES OF
ALKYL CHLORIDES AND PETROLEUM
FRACTIONS

Henry Trueheart Brown and Everett Gorin,
Dallas, Tex., assignors, by mesne assignments,
to Socony-Vacuum Oil Company, Incorporated,
New York, N. Y., a corporation of New York

Application December 26, 1944, Serial No. 569,837

6 Claims. (Cl. 260—666)

1

This invention relates to the conversion of normally gaseous hydrocarbons to hydrocarbons of higher molecular weight. More particularly this invention relates to the conversion of methane and natural gas to a mixture of normally liquid hydrocarbons of high octane number for use as motor fuel by converting the gaseous hydrocarbons to the corresponding halides and condensing the halides by means of a catalytic dehydrohalogeno-condensation process. Specifically the present invention has to do with the catalytic dehydrohalogeno-condensation of alkyl halides having less than four carbon atoms to the molecule, such as the chlorides of methane, ethane and propane in a reaction zone wherein petroleum fractions boiling above the gasoline range are undergoing simultaneous conversion to produce hydrocarbon fractions suitable for incorporation in motor fuel.

It is known to condense light alkyl halides by pyrolysis. For example, in the patent obtained by one of the present inventors, U. S. 2,320,274, entitled Conversion of normally gaseous hydrocarbons, it is taught to halogenate the hydrocarbons and then to pyrolyze the light alkyl halides at temperatures above 500° C. to produce benzene, acetylene and ethylene. In the copending application of Everett Gorin and Manuel H. Gorin entitled Catalytic conversion of normally gaseous hydrocarbons, Serial No. 556,746, filed October 2, 1944, now abandoned and refiled as Serial No. 677,402, on June 17, 1946, as a continuation-in-part, it has also been taught and claimed to catalytically dehydrohalogenate and condense methyl chloride to hydrocarbons having more than one carbon atom per molecule at temperatures below 500° C. We have found it advantageous to carry out the catalytic dehydrohalogenation-condensation of alkyl chlorides such as methyl chloride in the presence of hydrocarbons such as petroleum naphthas or a petroleum gas oil cut or in the presence of heavy synthetic oils such as a diesel fuel or gas oil cut from the Fischer-Tropsch product. Highly refractory gas oils containing polyalkylated aromatics such as hexamethyl benzene and polycyclic aromatics such as the alkyl naphthalenes may also be added although these materials are cracked to a much less extent than a paraffinic type of gas oil. By the term naphthas, as used in the specification and claims, we mean natural gasoline distillate stocks such as casinghead gasoline, light and heavy naphthas obtained from petroleum, and distilling within the range of from about 70° F. to about 500° F. By the term gas oil, we mean that fraction of natural petroleum or mixture of

2

synthetic hydrocarbons the distillation temperature limits of which lie within the range of 400° F. and 800° F. The addition of these relatively heavy hydrocarbon oils to the alkyl chlorides undergoing dehydrohalogenation and condensation not only reduces the yield of undesirable methane but also reduces the amount of free carbon produced by the reaction.

It, therefore, is an object of our invention to provide an improved process for converting normally gaseous hydrocarbons to normally liquid hydrocarbons. Another object is to produce from methane and natural gas, hydrocarbons having molecular weights higher than the major hydrocarbon components of natural gas which hydrocarbons in turn are susceptible to conversion to motor fuel. A further object is to catalytically condense the halide derivatives of methane and the halide derivatives of other hydrocarbon components of natural gas to higher molecular weight hydrocarbons in the same reaction zone wherein a hydrocarbon or normally liquid mixture of hydrocarbons of boiling range in or above that of motor gasoline is simultaneously converted to a mixture of hydrocarbons suitable for incorporation in motor fuel. In particular, it is the object of our invention to suppress the formation of carbon and methane in the dehydrohalogenation of methyl chloride by carrying out the reaction in the presence of a high boiling hydrocarbon oil. These and other objects will be apparent from the description of our invention.

The dehydrohalogeno-condensation of methyl chloride is effected by the aid of catalysts which possess both dehydrohalogenation and polymerization activity. Suitable catalysts are those which comprise an association of amphoteric and acidic oxides such as alumina on silica, zinc oxide on silica, boric oxide on alumina, beryllium oxide on silica or gallium oxide on silica. Other mixed oxide catalysts such as magnesia-silica, zirconia-silica or thoria-silica catalysts may be used. Pure amphoteric or acidic oxides may be used alone, such as for example, alumina, silica or titania. Active catalysts may also be prepared from naturally occurring materials such as by acid treating clays of the fuller's earth, bentonite, montmorillonite or attapulgus variety. These materials all show activity in the cracking of petroleum fractions and hence are suitable for use in our process. However, gel type catalysts having high porosity are preferred, and it is highly desirable that the catalyst be capable of withstanding high temperatures such as those produced by oxidative regeneration since in the

reaction cycle considerable carbon is deposited on the catalyst which must be removed in order to restore the catalyst activity. Alumina-silica catalysts prepared according to the procedure described in the above Serial No. 677,402 and containing from one to twenty percent alumina are particularly adaptable to use in our process.

We prefer to carry out the reaction under conditions such that a relatively large proportion of the gasoline product is derived from the methyl chloride. Hence a high ratio of methyl chloride to oil is employed. The weight percent of methyl chloride in the feed should be greater than 15 weight percent and preferably greater than 30 weight percent, while amounts as high as 85 or 90 weight percent of methyl chloride may be employed. The above catalysts are comparatively inactive at temperatures below 250° C. while in most cases temperatures above 300° C. are required to affect a reasonably rapid reaction. Temperature of operation should in no case exceed 500° C. and we prefer to operate at temperatures below 450° C., that is, within the range of from about 300° C. to about 450° C.

A wide range of pressures may be employed in converting the mixture of methyl chloride and heavy hydrocarbon oil to motor fuel blending products, such pressures varying from atmospheric to as high as 1800 or 2000 pounds per square inch. When the process is carried out in the neighborhood of atmospheric pressure and in the upper temperature range, both liquid and gaseous products are highly unsaturated. If pressures of 100 to 500 pounds per square inch are used, the temperature of operation being held below 425° C., the liquid products are substantially saturated while the olefin content of the gaseous products is relatively low. We prefer to operate at pressures from about atmospheric to about 500 pounds per square inch. The space velocity is adjusted to convert from 50 to 80 percent of the methyl chloride per pass and may vary within the range of from about 0.2 to 10.0 volumes of total liquid feed, that is, oil plus methyl chloride, per volume of catalyst space per hour depending on the temperature and pressure employed.

Relatively large quantities of isobutane are produced when operating under the above conditions which may be advantageously recycled to the process where it is converted by condensation with the methyl chloride to hydrocarbons of lower volatility suitable for incorporation in motor fuel. The isobutane also acts as a diluent for the methyl chloride and aids in keeping the instantaneous concentration of the methyl chloride at a low figure which is desirable for the most successful operation of our process since the rate of carbon formation is greatly reduced thereby. We may also maintain a low instantaneous concentration of methyl chloride by introducing the vaporized feed at a multiplicity of points to the stationary catalyst bed described below in our preferred method of operation.

Referring now to the drawing, towers 1 and 2 contain alumina gel-silica gel catalyst either as a continuous bed or disposed in trays. We prefer the latter method of packing these towers since the difficulty of controlling regeneration temperatures is reduced if the catalyst is maintained in a series of relatively shallow beds. Towers 1 and 2 are manifolded in such a manner that while one of these is on stream for the simultaneous condensation and cracking reactions, the other is undergoing oxidative regeneration

thus providing substantially continuous operation.

A feed comprising 50 to 75 parts by weight of methyl chloride admixed with a petroleum naphtha or gas oil is passed by means of pump 10 in line 11 to heat exchanger 12 at a pressure of from about 250 to about 300 pounds per square inch where heat is absorbed from the reaction product in line 13 and then flows through line 14 and heat exchanger 15 where additional heat is absorbed from hot regeneration gases in line 16. From exchanger 15 the hot feed passes via line 17 to manifold line 18 provided with valves 19 and 20 and connected with reactor feed manifold lines 21 and 22. With valve 19 in line 18 open and valve 20 closed, the feed is introduced to tower 1 through a multiplicity of valved feed lines leading from manifold line 21 at a temperature of about 400° C. and at a space velocity in tower 1 of about 3 volumes of liquid feed per volume of catalyst space per hour. Isobutane and ethyl chloride product described hereinbelow may be recycled by means of pump 23 in line 30 which joins manifold line 31 provided with valve 32 which is open and valve 33 which is closed. The isobutane and ethyl chloride product may be introduced to tower 1 via the main feed stream by closing valve 34 in line 30 and passing this recycle product through line 35 to recycle line 30 103 which joins line 11. Additional isobutane from the product is also furnished in the form of recycle methyl chloride-isobutane azeotrope, as hereinafter described, via recycle line 103.

The product from reaction tower 1 consisting of methane, ethylene, ethane, hydrogen chloride, unreacted methyl chloride, ethyl chloride, propylene, propane and C₄ hydrocarbons along with higher boiling hydrocarbons and unconverted gas oil is passed by drawoff line 40 to manifold product line 41 which is provided with valves 42 and 43, the latter being closed and the former open for delivery of the product to line 13 leading to heat exchanger 12 where the product is subjected to initial cooling. From exchanger 12 the product passes via line 44 to cooler 45 wherein the temperature of the product is further reduced to cause condensation of isobutane and higher boiling components of the decomposition product and adsorption of these in the gas oil. A considerable part of the C₃ hydrocarbons and of the hydrogen chloride decomposition product will also be absorbed in the liquid gas oil. From cooler 45 the relatively cold product passes via line 46 to vapor release drum 47 which is operated at approximately the same pressure as reaction tower 1. Non-condensable gases comprising methane, C₂ hydrocarbons and a part of the C₃ hydrocarbons and HCl pass overhead from drum 47 through pressure release valve 48 in line 49 to the hydrocarbon chlorination process for the production of alkyl chlorides as described and claimed in the copending joint application of C. M. Fontana and E. Gorin, entitled Manufacture of halogenated hydrocarbons, Serial No. 548,351, filed August 7, 1944. These alkyl chlorides may then be used as feed to our process.

The liquid product from drum 47 is passed by means of pump 50 in line 51 to fractionator 52 provided with heating means 53. Fractionator 52 operates as a stripper for removal of residual non-condensable hydrocarbon gases and hydrogen chloride from the condensable hydrocarbons and unconverted gas oil product. The pressure in tower 52 is maintained at 400 to 500 pounds per square inch. The overhead gas passes via line 54

to condenser 55 and the condensate passes thence via line 56 to reflux drum 57. Uncondensed gas comprising the last traces of methane and the C₂ gases pass overhead from drum 57 the pressure being controlled by means of valve 58 in line 59 which connects with line 49 leading to the alkyl chloride manufacturing process. Hydrogen chloride condensate in reflux drum 57 is removed therefrom by pump 60 in line 61 to be returned in part to tower 52 as reflux through valved line 62, excess condensate being sent via valved line 63 to the aforesaid alkyl chloride manufacturing process. It is not only highly desirable to recover hydrogen chloride from our process for reuse in producing alkyl chloride feed stock but also desirable to remove the hydrogen chloride from the recycle stock since large amounts of hydrogen chloride have an inhibiting effect on the course of the alkyl chloride condensation reaction. It is desirable to maintain the hydrogen chloride concentration below 35 percent of the total gas and in any case the concentration should not constitute over 60 mole percent of the total conversion products in reactor effluent line 13.

The liquid product from fractionator 52 is transferred via pressure release valve 64 in line 65 to debutanizer tower 66 for removal of propane, propylene, the C₄ fraction, unconverted methyl chloride and ethyl chloride from the higher boiling product. The overhead from tower 66 may also contain hydrogen chloride in minor amounts which is retained in the liquid product from tower 52 as a result of the relatively high pressure fractionation in tower 52. Tower 66 is operated at a pressure of from about 100 to about 200 pounds per square inch and is provided with reboiler means 67. The overhead gaseous product from tower 66 passes via line 68, condenser 69 and line 70 to reflux drum 71 from which non-condensed gas, primarily hydrogen chloride, passes via valved line 72 to line 63 for use in producing methyl chloride or other alkyl chlorides as described in the aforementioned Serial No. 548,351. Condensate from reflux drum 71 is picked up by pump 73 in line 74, a part being transferred through valved line 75 to tower 66 as reflux and the remainder is passed via valved line 76 to depropanizer tower 77. The components of the stream in line 76 are all suitable for recycle to the reaction zone and hence valved line 30 is provided, which leads from line 76 directly to manifold line 31. As stated hereinabove, this recycle product may be diverted to the main feed stream in line 11 via valved line 35 and recycle line 103.

That part of the stream of relatively light hydrocarbons in line 76 not diverted as recycle through line 30 is fractionated in tower 77 to separate propane and propylene from the C₄ hydrocarbons and alkyl chlorides. Tower 77 is operated at a pressure of from about 200 to 250 pounds per square inch with tower top temperature maintained at about 35° C. to about 45° C., tower 77 being provided with reboiler means 78. The overhead consisting of propylene and propane passes via line 79, condenser 80 and line 81 to reflux drum 82 whence any uncondensed propylene passes overhead through line 83 to recycle line 30. Condensate is removed from drum 82 by means of pump 84 in line 85 for transfer in part to tower 77 as reflux through line 86 and the remainder, comprising relatively pure propane, may be sent to storage via line 87 or it may be recycled via line 30 to reaction tower 1.

The bottom product from tower 77 is trans-

ferred via line 90 and pressure release valve 91 to deisobutanizer tower 92 which is provided with reboiler means 93. Methyl chloride forms an azeotrope with isobutane and hence the overhead from tower 92 consists primarily of methyl chloride-isobutane azeotrope boiling at about -25.6° C. at atmospheric pressure, provided these components are present in the proper proportions. This azeotrope consists of approximately 77 mol percent methyl chloride and 23 mol percent isobutane. Provision is made for adding methyl chloride to line 90 via line 94 by means of pump 95 for increasing the amount of methyl chloride in tower 92 when the conversion of methyl chloride in reaction tower 1 is sufficiently high to leave insufficient unconverted methyl chloride to form the desired azeotrope with isobutane product. The overhead product from tower 92 consisting of the azeotrope and a relatively small amount of propane passes overhead through line 96, condenser 97 and line 98 to reflux drum 99 whence the condensate is sent in part by means of pump 100 in line 101 and via valved line 102 to tower 92 as reflux, the remainder being passed via valved line 103 as recycle to main feed line 11. Any accumulation of gaseous propane in drum 99 is removed via line 104 to storage. The C₄ bottom fraction which is removed from tower 92 via line 105 contains some ethyl chloride which may be separated by scrubbing with an alcohol-water mixture and the separated ethyl chloride may be recycled to reaction tower 1 while the C₄ fraction which may contain excess isobutane over that required to form the azeotrope with methyl chloride may be withdrawn from the system and subjected to alkylation and/or isomerization reactions to produce aviation grade gasoline.

Returning now to debutanizer tower 66 the bottom product, consisting of C₅ and higher hydrocarbon reaction products and unconverted gas oil, is withdrawn through line 106 and pressure release valve 107 and is passed to fractionator 108 for the separation of motor fuel product. Fractionator 108 is provided with reboiler means 109 and conventional 375° to 400° F. endpoint gasoline line is taken overhead through line 110, condenser 111 and line 112 to reflux drum 113.

Condensate in drum 113 is picked up by pump 114 in line 115, a part of the liquid being returned to tower 108 as reflux through line 116 and the remainder is withdrawn through line 117 and given a caustic wash to remove any traces of hydrogen chloride prior to incorporation in motor fuel. The bottom product from tower 108 of distillation range above that of motor gasoline and consisting primarily of unconverted gas oil is withdrawn through line 118 and is recycled via line 103 to feed line 11 a part being eliminated from the process through line 119 to prevent excessive accumulation of highly cyclized refractory cycle stock.

When a reactor has been on stream for an interval up to 90 minutes depending on the operating conditions relative to space velocity, temperature and pressure, sufficient carbon will have accumulated on the catalyst to necessitate reactivation. This is accomplished after purging the reactor of hydrogen chloride and other vapors by passing air through the reactor, the air being diluted with flue gas in order to control the rate of oxidation and to maintain the regeneration temperature below about 650° C., preferably below about 600° C. It is desirable to purge the reactor of hydrogen chloride and hydrocarbon vapors before regeneration since the combustion of the hydrocarbons results in the formation of water

vapor which in the presence of hydrogen chloride aggravates corrosion problems. The purging and reactivation of the catalyst in reaction zone 2, that is tower 2, is carried out while tower 1 is on stream as described hereinabove.

Tower 2 is isolated for purging before regeneration by closing valve 123 in line 122, valve 33 in line 31, valve 20 in line 18, valve 143 in line 142, valve 145 in line 146, valve 43 in line 41 and valve 125 in line 40. Methane purge gas is introduced via line 121 and passes via lines 122 and 31 to reactor 2 for removal of residual hydrogen chloride, unreacted alkyl halides and hydrocarbon vapors. The purge gas leaves reactor 2 through line 151 and thence passes through open valve 126 in manifold line 127 and through open valve 129 in line 130 to line 49 for transfer to the alkyl chloride production unit described in the hereinabove mentioned copending application, Serial No. 548,351. The methane purging step is followed by a short flue gas purge to clear reactor 2 of methane prior to the reactivation step.

Referring now to the reactivation step following the purging of reactor 2, a mixture of air and flue gas is introduced to the system by means of compressor 140 in line 141. The extent of dilution of oxygen in the regenerating gas should be such that temperatures in excess of 650° C. are avoided and preferably the temperature should not exceed 600° C. since synthetic alumina-silica catalyst and also acid treated clays tend to become permanently deactivated at higher temperatures.

The flue gas diluted air is passed from line 141 to manifold line 142, which is provided with valves 143 and 144, and thence to line 22 for introduction to tower 2 via manifold and valved feed lines leading from line 22. The regeneration zone is isolated by closing valve 144 in line 142, valve 20 in line 18, valve 147 in line 146, valve 43 in line 41 and valve 126 in line 127 and provision for continuous flow of regeneration gas is made by maintaining valve 143 in line 142 and valve 145 in line 146 in the open position. The regeneration gas passes from tower 2 through line 151 to line 146 and thence through line 16 to heat exchanger 15 whence it is eliminated from the system through valved line 149. If desired, a part of the spent regeneration gas may be recycled to line 141 through valved line 150 for dilution of fresh regeneration air. The flow of regeneration gas is continued for a temperature adjustment period following complete reactivation of the catalyst until the catalyst bed temperature has lowered to such a level that fresh feed will be held within the desired temperature range for the conversion cycle. The purge gas should contain no oxygen during this purging operation and hence steam may be substituted for the flue gas for the final temperature adjustment operation.

Although we have described our process as being carried out at pressures of 250 to 300 pounds per square inch, higher or lower pressures may be used. The simultaneous condensation and catalytic cracking reactions may be carried out at lower pressures, for example, of the order of atmospheric to 50 pounds per square inch gauge. However, such type operation involves greater expenditure of capital for compression equipment for separation of predominantly gaseous hydrocarbon product. Certain advantages favor low pressure operation. For example, the carbon deposited on the catalyst may be removed more advantageously by operating the oxidative reactivation step by the well known hindered flow type

procedure which is adaptable only to relatively low pressure operation. Oxidative regeneration temperatures are more uniform and more easily controlled in this type operation. Hindered flow, that is, suspended powdered catalyst operation may also be used for the conversion cycle if the pressure is maintained below about 75 pounds per square inch. We may also adopt other methods of catalytic contacting to our process of simultaneously converting alkyl chlorides and naphthas or gas oil to liquid hydrocarbons of motor fuel distillation range. For example, the various types of moving catalyst bed techniques well known in the art of hydrocarbon conversion, particularly in the art of converting petroleum hydrocarbons and hydrocarbon mixtures, may be used if relatively low pressure operation is followed.

The improvements effected in the dehydrohalogenation-condensation of methyl chloride and in the cracking of cetane by carrying out the processes simultaneously are illustrated by the experiments listed in the table below. All the experiments were carried out at 425° C. and atmospheric pressure with fresh samples of an alumina-silica mixed gel catalyst prepared according to the procedure outlined in the above copending application Serial No. 556,746. The mol ratio of silica to alumina in the catalyst was about 7/1.

¹ Percent by weight.

The comparison of the behavior of mixtures of cetane and methyl chloride with the pure materials by themselves was made at the same value of the vapor space velocity, i. e., at approximately the same times of contact with the catalyst. The space velocity is expressed in terms of volume of vaporous feed, calculated as the volume the material would have if it were a perfect gas at normal conditions of temperature and pressure, passed over unit volume of catalyst per unit time.

The weight percent yields of carbon and of methane are calculated from the weight of carbon and methane formed respectively, divided by the total weight of C₁ through C₈ hydrocarbons plus carbon formed in the cracking of the cetane. The yields of carbon and methane derived from the methyl chloride are expressed in terms of mols of carbon and methane formed respectively, multiplied by one hundred and divided by the number of mols of methyl chloride decomposed. The last line of the table gives the mol percent of methyl chloride which decomposed to form C₂ + hydrocarbons. In calculating the yields of methane and carbon formed from the methyl chloride only in experiment 3, it was assumed that the yields of carbon and methane derived from the cetane were the same as were obtained in experiment 4 where the same percentage cracking of the cetane was incurred.

The advantages of our process are seen quite clearly from these examples. Comparing experiments 1, 2, and 3, it is seen that by carrying out the dehydrohalogenation of the methyl chloride and cracking the cetane simultaneously, the reaction rates are mutually enhanced. The percent of methyl chloride decomposed at the same space velocity increases from 57.8 to 68.4 by carrying out the reaction in the presence of cetane while the percent of cetane cracked, likewise, increases from 24.7 to 54.0. An outstanding improvement in the yields of C₂+ hydrocarbons derived from the methyl chloride is simultaneously effected, increasing from 65.1 percent in the absence of cetane to 84.9 percent in the presence of cetane and the yields of carbon and methane individually are reduced from 24.7 and 10.2 percent to 12.2 and 2.9 percent, respectively.

Having thus described the nature of our invention and means for practicing the same, but without intending thereby to limit our invention to such specific means, save as expressly set forth in the appended claims, we claim as new:

1. A process for the condensation of alkyl chlorides having less than four carbon atoms per molecule to produce hydrocarbons having a greater number of carbon atoms than the alkyl chloride treated which comprises passing a stream consisting essentially of a mixture of said alkyl chloride and a higher than gasoline-boiling petroleum fraction containing from 15 to 90 weight per cent of said alkyl chloride through a reaction zone containing a solid, metallic oxide hydrocarbon-cracking catalyst at a temperature of from about 300° C. to about 450° C. and at a rate such that from about 50% to about 80% of the alkyl chloride content of the feed mixture is converted per pass, and recovering the hydrocarbon content of the effluent stream from the reaction zone.

2. A process for the condensation of alkyl chlorides having less than four carbon atoms per molecule to produce hydrocarbons having a greater number of carbon atoms than the alkyl chloride treated which comprises passing a stream consisting essentially of a mixture of said alkyl chloride and a gas oil containing from 15 to 90 weight per cent of said alkyl chloride through a reaction zone containing a solid, metallic oxide hydrocarbon-cracking catalyst at a temperature of from about 250° C. to about 500° C. and at a rate such that from about 50% to about 80% of the alkyl chloride content of the feed mixture is converted per pass, and recovering the hydrocarbon content of the effluent stream from the reaction zone.

3. A process for the condensation of alkyl chlorides having less than four carbon atoms per molecule to produce hydrocarbons having a greater number of carbon atoms than the alkyl chloride treated which comprises passing a stream consisting essentially of a mixture of said alkyl chloride and a higher than gasoline-boiling petroleum fraction containing from 30 to 90 weight per cent of said alkyl chloride through a reaction zone containing a solid, metallic oxide hydrocarbon-cracking catalyst at a temperature of from about 300° C. to about 450° C. and at a rate such that from about 50% to about 80% of the alkyl chloride content of the feed mixture is converted per pass, and recovering the hydro-

carbon content of the effluent stream from the reaction zone.

4. A process for the condensation of methyl chloride to produce hydrocarbons of at least two carbon atoms therefrom which comprises passing a stream consisting essentially of a mixture of said methyl chloride and a gas oil and containing from 30 to 90 weight per cent of said methyl chloride through a reaction zone containing a solid, metallic oxide hydrocarbon-cracking catalyst at a temperature of from about 300° C. to about 450° C. and at a rate such that from about 50% to about 80% of the methyl chloride content of the feed mixture is converted per pass, and recovering the hydrocarbon content of the effluent stream from the reaction zone.

5. A process for the condensation of alkyl chlorides having less than four carbon atoms per molecule to produce hydrocarbons having a greater number of carbon atoms than the alkyl chloride treated which comprises passing a stream consisting essentially of a mixture of said alkyl chloride and a higher than gasoline-boiling petroleum fraction containing from 15 to 90 weight per cent of said alkyl chloride through a reaction zone containing an alumina-silica catalyst at a temperature of from about 300° C. to about 450° C. and at a rate such that from about 50% to about 80% of the alkyl chloride content of the feed mixture is converted per pass, and recovering the hydrocarbon content of the effluent stream from the reaction zone.

6. A process for the condensation of methyl chloride to produce hydrocarbons having at least two carbon atoms per molecule therefrom which comprises passing a stream consisting essentially of a mixture of said methyl chloride and a gas oil and containing from 30 to 90 weight per cent of said methyl chloride through a reaction zone containing an alumina-silica catalyst at a temperature of from about 300° C. to about 450° C. and at a rate such that from about 50% to about 80% of the methyl chloride content of the feed mixture is converted per pass, and recovering the hydrocarbon content of the effluent stream from the reaction zone.
